UNITED STATES PATENT OFFICE.

JOHN D. HICKMAN, OF ANDERSON, INDIANA.

TROLLEY-POLE.

SPECIFICATION forming part of Letters Patent No. 703,921, dated July 1, 1902.

Application filed October 11, 1901. Serial No. 78,332. (No model.)

To all whom it may concern:

Be it known that I, JOHN D. HICKMAN, a citizen of the United States, and a resident of Anderson, in the county of Madison and State of Indiana, have made a certain new and useful Invention in Trolley-Poles; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a perspective view of my pole. Fig. 2 is a side elevation of the same, partly in section, the raised position of head B being shown in dotted lines. Fig. 3 is a detail section of a modified form of spring for the head of the pole.

This invention has relation to trolley-poles, and has for its object the provision of a novel form of head for such pole with the object of preventing the trolley-wheel from becoming disengaged from the conducting-wire and allowing the ready disengagement thereof by means of the pull-cord without disturbing the adjustment of the pole proper.

With this object in view the invention consists in the novel construction and combination of parts, all as hereinafter described, and pointed out in the appended claims.

Referring to the accompanying drawings, the letter A designates the trolley-pole, and B the head thereof, usually about two or two and one-half feet in length and hinged to the pole at its lower end at b.

C is a plate-spring disposed below the head B and secured to depending extension a of the pole, the upper end of said spring carrying a concave or grooved antifriction-roller C', the flanges of which embrace the head B, and thus aid in keeping the head in the same vertical plane as the pole and preventing disengagement of the spring from the head, the tension of the spring being arranged to exert a strong upward pressure upon the head,

such as to carry it as much as twelve inches upwardly or out of line when the trolley is disengaged from its wire.

a' a² are the securing-bolts for plate-spring to extension a, the forward of said bolts a' being extended to form a stop for the head to limit its downward swing when the head is in line with the pole. The upper end of the pole is also provided with a stop a³ to limit the upward swing of the head.

The pull-cord D is attached to the head near its upper portion for disengaging the trolley from its wire.

Fig. 3 of the drawings illustrates a modification of my invention in which a coil-spring E surrounds the hinge-pin of the head and is arranged to exert an upward pressure upon the head in place of the plate-spring; but I use the plate-spring in my preferred construction.

Having thus described my invention, what I claim as new, and desire to secure by Letters Patent, is—

1. The combination with a trolley-pole, of a head pivoted thereto, the plate-spring carried by said pole, and having the bracing-roller at its upper end engaging said head, and preventing lateral displacement thereof, and stops for limiting the swing of said head in both directions, substantially as specified.

2. The combination with a trolley-pole, of a head pivoted thereto, the plate-spring carried by said pole, and having the bracing-grooved roller at its upper end embracing said head, the securing-bolt for said spring extended to form a stop for limiting the downward swing of said head, and the stop for limiting the upward swing of said head, substantially as specified.

In testimony whereof I affix my signature in presence of two witnesses.

JOHN D. HICKMAN.
